(57) **CLAIM**

The ornamental design for an E-board pen, as shown and described.

DESCRIPTION

FIG. 1 is a front perspective view of an E-board pen showing my new design;

FIG. 2 is a front view thereof;

FIG. 3 is a top view thereof; and,

FIG. 4 is a bottom view thereof.

The rear view, the left view and right view are identical to the front view of the E-board pen.
